UNITED STATES PATENT OFFICE.

GEORGE K. CUMMINGS, OF NEW YORK, N. Y.

DESIGN FOR A PRISM-WINDOW.

SPECIFICATION forming part of Design No. 29,808, dated December 13, 1898.

Application filed August 15, 1898. Serial No. 688,630. Term of patent 7 years.

To all whom it may concern:

Be it known that I, GEORGE K. CUMMINGS, a citizen of the United States, residing at New York, in the county and State of New York, have invented and produced a new and useful Design for Prism-Windows, of which the following is a specification.

My invention relates to a new design for prism-windows and is illustrated in the accompanying drawings, in which—

Figure 1 is an elevation or front view of a prism-window embodying my said design, and Fig. 2 is a transverse cross-section through the middle of the window.

The design consists of a number of variously-shaped panes, plates, or lights of prism-glass grouped together so as to form a single window or design.

The parallel cross-lines of the drawings represent the angular edges of the glass prisms which, with a body portion of glass, constitute the said panes, plates, or lights. The heavier doubled lines of the drawings represent the framework.

The design is described as follows: Within 25 a rectangular parallelogram appears a row of oval or elliptical figures, each overlapping upon its neighbor on either hand and inclosing a diamond-shaped prism-light whose sides curve inwardly, four elongated elliptical 30 prism-lights, and four that are somewhat shield-shaped. At the top, bottom, and sides of the design appear prism-lights of triangular and diamond-like shape.

The design presents the general appearance of a row of overlapping ovals with central diamonds. 35

I claim—

The design for a prism-window as herein shown and described. 40

In testimony whereof I have signed my name to this specification in the presence of two subscribing witnesses.

GEORGE K. CUMMINGS.

Witnesses:

EDWIN SEGER,
SIDNEY MANN.
